United States Patent Office

Des. 207,297
Patented Mar. 28, 1967

207,297

SHAVER

Harmon L. Shaw and John G. Williamson, Charlotte, N.C., assignors to Timac, Inc., Charlotte, N.C., a corporation of North Carolina

Filed Feb. 21, 1966, Ser. No. 1,128

Term of patent 14 years

(Cl. D95—3)

The dominant features of our design reside in those portions shown in full lines.

We claim:

The ornamental design for a shaver, as shown and described.
